United States Patent Office.

ASA SNYDER, OF RICHMOND, VIRGINIA.

Letters Patent No. 96,497, dated November 2, 1869.

COOKING-STOVE

The Schedule referred to in these Letters Patent and making part of the same.

To all whom it may concern:

Be it known that I, ASA SNYDER, of Richmond, in the county of Henrico, and State of Virginia, have invented a new and useful Improvement in Stoves; and I do hereby declare that the following is a full, clear, and exact description of the construction and operation of the same, reference being had to the accompanying drawings, making a part of this specification, in which—

Figure 1 is the front portion of a transverse vertical section; and

Figure 2 is a longitudinal vertical section.

This invention relates to stoves for heating or cooking-purposes, having hollow-walled fire chambers, and hollow grates, and perforations in the inner walls of the fire-chambers, for conducting air, in a heated condition, to the fire.

The invention consists in providing, in combination with such hollow-walled fire-chamber and hollow grate, a damper, in the flue leading from the hearth to the grate in the bottom of the fire-chamber, for the purpose of completely closing such flue, and preventing cold air from finding access through it to the fire-chamber, and the heated currents drawn into the same from above.

In the drawings—

A is the fire-chamber, having double walls a' , the space between which receives, through apertures a'' , in its bottom, the cold air that passes the outer wall of the stove at b , and is discharged into the products of combustion from the fire, through the orifices a''' , in the inner wall a of the fire-chamber.

B is the hollow grate, receiving external air through its trunnions, b' , and discharging it through orifices b'' , in the under sides of the grate-bars.

A portion also of the external air, received at the apertures b , also enters the fire at its bottom, through the openings in the bed-plate supporting the grate.

It will be perceived, that with this construction, there are currents of air, heated by contact with the inner and outer walls a' of the fire-chamber, continually traversing the hollow spaces surrounding the latter.

But it is necessary to have some opening, by which the debris from the grate shall find their way to the hearth, and such opening is afforded by the flue C; and to prevent cold air from entering by this flue, and cooling the heated currents, I place in it a damper, c, completely closing it, and only to be opened for the discharge of the debris.

By this arrangement, the fire-chamber is surrounded at the bottom as well as the sides, with a hot-air space, and no cold air can reach it, even though the front doors and dampers be left open.

The damper c may be a sliding as well as a revolving one, and may appropriately be termed a separation-plate.

Having thus described my invention,

What I claim as new, and desire to secure by Letters Patent, is—

In combination with the hollow-walled fire-chamber and hollow grate herein described, the separation-plate c, arranged and operating substantially as described.

ASA SNYDER.
